UNITED STATES PATENT OFFICE.

FRANK E. AURAND, OF OAK PARK, ILLINOIS, ASSIGNOR OF ONE-HALF TO GUY W. LUNN,
OF CHICAGO, ILLINOIS.

COMMUTATOR-SLOTTING DEVICE.

1,260,125.

Specification of Letters Patent. Patented Mar. 19, 1918.

Application filed May 11, 1917. Serial No. 167,983.

To all whom it may concern:

Be it known that I, FRANK E. AURAND, a citizen of the United States, residing at Oak Park, in the county of Cook and State of Illinois, have invented new and useful Improvements in Commutator-Slotting Devices, of which the following is a specification.

This invention is an improved machine for slotting commutators by cutting out the mica or other insulating material between the bars of a commutator, the object of the invention being to provide an improved machine of this kind which is simple in construction, is light and portable and adapted for manual manipulation and which may be used on commutators without the necessity of removing the motor end shields and brush holders. Another object is to provide an improved machine of this character which is adapted for cutting the slots on commutators that have been worn to an uneven surface as well as on commutators that are true or faced. Another object is to provide an improved machine of this kind which can be caused to follow the curvature of a worn commutator and cut the insulation to an even depth regardless of the worn condition of the commutator surface and at the same time keep the cutting saw true with the center of the commutator. Another object is to provide an improved machine of this kind which is adjustable and adapted to be used on commutators of different diameters. Another object is to provide an improved commutator slotting device which may be used on the commutators of motors or generators whether the same are rough and ridged or smooth and true, and without the necessity of removing the end shields or brush holders of the motor or generator and also without the necessity of employing special frames clamped to the commutator or frame keeping the cutting tool in alinement.

A further object is to provide an improved commutator slotting machine which may be used without danger of injuring the commutator bars.

With the above and other objects in view the invention consists in the construction, combination and arrangement of devices hereinafter described and claimed.

In the accompanying drawings:—

Fig. 1 is a side elevation, partly in section, of a commutator slotting machine constructed and arranged in accordance with my invention.

Fig. 2 is an elevation of the same showing the reverse side from that shown in Fig. 1.

Fig. 3 is a plan of the same.

Fig. 4 is a front elevation of the same, showing the same as arranged for use on a commutator.

Fig. 5 is an elevation partly in section, showing a modified construction of my improved commutator slotting machine.

Fig. 6 is a detailed transverse sectional view on the plane indicated by the line 6—6 of Fig. 3.

In accordance with my invention I provide a head 1 which has flat vertical opposite sides 2, 3 and which is provided at the front end with a pair of spaced forwardly extending bearings 4 and is provided at the rear side with a tubular portion 5 which is internally threaded at 6. A longitudinal shaft 7 is mounted in a bearing which is concentric with the tubular portion 5 and said shaft is provided at its front end with a worm 8.

A transversely arranged shaft 9 is mounted in the bearings 4 and is provided at the center with a worm gear 10 which is arranged between the bearings 4 and is engaged by the worm 8. At the right-hand end of the shaft, corresponding with the side 3 of the head is a revoluble cutter element 11 which is here shown as a circular saw and which is secured to and driven by said shaft. To the under side of the bearing 4 nearest the saw is secured a segmental shoe 12 which in practice is preferably made of fiber and which serves to bear on one of the commutator bars when the machine is in use, to support the machine on the commutator and permit the machine to be moved on the commutator in line with the bars to permit the operation of the saw and adapt the saw to cut the mica or other insulating material between the commutator bars. The shoe also gages the depth of the cuts made by the saw, as will be understood.

A vertically arranged bracket 13 is secured by screws 14 in a vertical groove 15 in the side 3 of the head. The lower end of said bracket projects downwardly below the head

and a guide element 15 which is made of thin metal is pivotally connected at its front end to the lower portion of said bracket as by means of a screw 16. The said guide element is arranged directly in line with the saw and the lower edge of the guide element operates behind and in the slot formed or cut by the saw, the guide element serving to steady the slotting machine on the work and 10 also enabling the slotting machine to be moved manually in line with the commutator bars as required to direct the saw and cause the saw to cut the mica or other insulating material between the commutator 15 bars. A spring 17 is secured to the rear side of the bracket 13 and bears downwardly on the upper edge of the guide element as shown.

The side 2 of the head also has a vertical 20 groove 18 in which a bracket 19 is mounted for vertical adjustment. Said bracket has a vertical slot 20 for the reception of the screws 21 which secure said bracket to the head, the slot enabling the bracket to be vertically adjusted and the screws enabling the bracket to be secured to any desired vertical adjustment, as will be understood. Said bracket has a forwardly extending arm 22 at its lower end and on which a supporting 25 roller 23 is mounted. The stub shaft or axle of the roller is indicated at 24. The roller is made of fiber and serves to rest upon the commutator and to support part of the weight of the cutting head and also serves to 30 facilitate the manipulation of the machine by the user.

Within the scope of my invention any suitable means may be employed for driving the worm shaft 8 and thereby driving the 40 slot cutting saw. In the form of the invention shown in Figs. 1 to 4 the said shaft 7 is driven by an electric motor 25 the shaft 26 of which is connected by a coupling 27 to the inner end of the worm shaft 7. The 45 casing of the motor is bolted at one side to a hollow handle section 28 the front end of which is provided with an exteriorly threaded tubular projection 29 which is screwed in the tubular portion 5 of the head 1 as shown. The outer or rear end of the motor casing is 50 bolted to a hollow handle section 30. The conducting cables 31 pass through the handle section 30 as shown. It will be understood that the handle of this form of my invention 55 may be readily grasped by the workman and that the slotting machine may be readily controlled and manipulated by the workman in such manner as to cause the same to cut the commutator slots. In Fig. 5 of the drawing I show a hollow handle 32 which is attached as at 33 to the tubular portion of the head in lieu of the handle hereinbefore described. A shaft 34 extends longitudinally through the center of 65 the hollow handle 32 and is mounted in bear-

ings 35, 36 and is connected to the worm shaft 7 by a coupling 37. The shaft may be connected to a flexible shaft driven by any suitable form or type of motor.

While I have herein shown and described 70 a preferred form of my invention I would have it understood that changes may be made in the form, proportion and construction of the several parts, without departing from the spirit of my invention and within 75 the scope of the appended claims. I would also have it understood that while the invention is especially adapted for use in cutting out the slots of commutators it may also be used for other analogous purposes and for 80 cutting fiber blocks, sheet mica, asbestos, lumber, and the like.

Having thus described my invention, I claim:—

1. In a commutator slotting machine, a 85 head, a cutting element revolvably mounted on one side of the head, a guide arranged behind and in line with the cutting element to operate in the slot cut thereby, a shoe on the under side of the head and near the cutting element to bear on the work, a bracket on the side of the head opposite that on which the cutting element is located and provided with a roller to bear on the work, a handle projecting from the head and arranged parallel with the plane of the cutting element and means to operate the cutting element and including a shaft arranged in the handle. 90

2. In a commutator slotting machine, a 100 head, a cutting element revolvably mounted on the head, means to actuate the cutting element, a guiding element pivotally connected to the head and arranged behind and in line with the cutting element to operate 105 in the slot made by the cutting element, a spring bearing downwardly on said guide and supporting means for the head and arranged to bear on the work and to permit sliding movement of the machine on the 110 work.

3. In a commutator slotting machine a 115 head, a cutting element revolvably mounted on the head, a guide arranged behind and in line with the cutting element to operate in the slot cut thereby, supporting means for the head and arranged to bear on the work to permit sliding movement of the machine on the work, said supporting means comprising a shoe arranged near the cutting element and a bracket secured to the head and spaced from the cutting element and a roller carried by said bracket and to bear 120 on the work.

4. In a commutator slotting machine a 125 head, a cutting element revolvably mounted on the head, a guide arranged behind and in line with the cutting element to operate in the slot cut thereby, supporting means for the head and arranged to bear on the 130

work to permit sliding movement of the machine on the work, said supporting means comprising a shoe arranged near the cutting element and a bracket secured to the head 5 and spaced from the cutting element and a roller carried by said bracket and to bear on the work, the said bracket being vertically adjustable on the head.

5. In a commutator slotting machine a head, a driving shaft arranged longitudinally of the head and mounted in a bearing therein, means to rotate said shaft, a shaft arranged transversely of the head, geared to the driving shaft and provided with a 10 revolute cutting element, a guide connected to the head and arranged to operate in a slot made by the cutting element and sup-

porting means for the head arranged to bear on the work and permit sliding movement of the head on the work.

6. In a commutator slotting machine, a head, a driving shaft arranged longitudinally in the head, mounted in a bearing therein and provided at the front end with a worm, a shaft arranged transversely of the head and mounted in bearings therein, a cutting element on the last-named shaft, a worm gear also on the last-named shaft and engaged by the worm, a handle connected to the head and driving means for the driving shaft, said driving means being carried by the handle. 20 25 30

In testimony whereof I affix my signature.
FRANK E. AURAND.
